UNITED STATES PATENT OFFICE.

EUGENE GASSMANN, OF BROOKLYN, NEW YORK, ASSIGNOR TO EISEMANN MAGNETO CO., OF BROOKLYN, NEW YORK, A CORPORATION OF NEW YORK.

DISTRIBUTER FOR ELECTRICAL IGNITION SYSTEMS FOR INTERNAL-COMBUSTION ENGINES.

1,120,301.

Specification of Letters Patent.

Patented Dec. 8, 1914.

Application filed November 28, 1913. Serial No. 803,587.

To all whom it may concern:

Be it known that I, EUGENE GASSMANN, a citizen of Germany, and a resident of the borough of Brooklyn, county of Kings, and 5 State of New York, have invented certain new and useful Improvements in Distribut-
10 utes for Electrical Ignition Systems for Internal-Combustion Engines, of which the following is a full, clear, and exact speci-
15 fication.

This invention relates to electrical igni-
10 tion systems for internal combustion en-
gines, and consists of the herein shown and
described improvement in the construction
15 of distributors which constitute an essential
part of such ignition devices employed for
multi-cylindrical engines. It is well known
that the ignition devices for such engines
20 are employed on automobiles, trucks, and
other similar vehicles, and are almost con-
tinually exposed to atmospheric conditions,
dampness and rain; it is also well known,
25 that if moisture or water penetrate into the
electrical connections, or in the contacts,
short circuiting of the apparatus and break-
downs of the engine result. Many attempts
30 were made, in different ways, to "water-
proof" the connections, etc., but the ob-
stacle to success of these attempts was
always found in the connections of the elec-
35 trical conduits, entering from the outside
into the distributing device, and which were
thus exposed, or rendered accessible to
dampness, rain, etc.

40 The object of my invention is to arrange
the parts of the distributor, and to provide
means for connecting its parts with their
respective conduits, whereby this source of
danger is entirely avoided.

45 In the accompanying drawing a distrib-
uter, constructed according to my invention,
is shown—Figure 1 being a front elevation;
Fig. 2, a longitudinal sectional view there-
of, on lines 2—2 indicated in Fig. 1, some
50 parts being shown in elevation to aid in a
clearer representation of the device; Fig. 3
is a view similar to Fig. 2, showing the ar-
rangement of the connection from the col-
lector brush to the distributor contact.

55 The operative parts of the distributor are
located in the casing *a*. The rotating disk *c*
is secured to the driven cog-wheel *b*, rotat-
ably mounted on shaft *d*, and driven by cog-
wheel *b'*, set on the armature shaft of the

magneto, whereon also the collector ring *e* 55
is fixed. The contact segments for effecting
intermittent electrical connections between
the central brush *f* and the brushes *g*, *g'*, *g''*,
etc., are affixed to the disk *c*, and the brushes
60 *g*, *g'*, *g''*, etc., as well as the central brush *f*,
and the collector brush *h*, are mounted in
the cover *a'* of the distributor casing.
Brushes *f* and *g*, *g'*, *g''*, etc., must be electric-
ally connected with the metallic cores *q* of
cables *o*, *o'*, *o''*, *o'''*, etc., and to effect their 65
connections to be safely protected from at-
mospheric influence, dampness, etc., I make
the cover *a* of the distributor casing of sub-
stantial thickness, and arrange the connec-
tions within, in the manner shown, and 70
hereinafter described. For this purpose the
interiorly screw-threaded recesses *i* are made
in the cover, in the points where the brushes
are to be located. The tubular metallic lin-
ings *k*, screw-threaded exteriorly and inter- 75
iorly, are screwed into these interiorly
screw-threaded recesses *i*. These tubular
metallic linings *k* are closed at their inner
ends and transversely perforated at *p*
to admit the metallic cores of the cables. 80
The interior termini of the linings *k* are
concaved, and conically pointed screws *r* are
screwed in, to clamp the cores of the cables
to obtain a close contact of the metallic
cores *q* with the linings *k* and safely perma- 85
nent connections. Metallic springs *l* are
then set in the tubular linings *k* against the
heads of the screws *r*, and then the brushes
g, *g'*, *g''*, etc., are inserted against the springs
l, which then serve to yieldingly press the 90
brushes against the distributor disk *c*, and
to hold them in close contact with the dis-
tributor segments.

95 Radial bores *t* are drilled from points on
the periphery of the cover *a* of the distrib-
uter casing, one to each of the terminals of
the recesses *i*, in which the brushes *g*, *g'*, *g''*,
etc., are set. The radial bores are made just
sufficiently large to admit the insulations of
cables *o*, *o'*, *o''* etc., which are then snugly 100
fitting therein, and the bared ends of the
cable cores are electrically connected by
screws *r* to the tubular metallic linings *k*, in
which the brushes *g*, *g'*, *g''*, etc., are set as
hereinbefore explained.

105 The collector brush *h* is set in a similarly
constructed metallic lining *k'*, screwed in
the radial recess *i'* in the base of the cover

a'. The lining *k'* is connected by the metallic strip *u* to the lining *k²*, an intermediate device, connected by the cable *m* with the central brush *f* in the same way as explained with reference to the brushes *g*, *g'*, *g²*, etc. The intermediate device *k²* and its connection, the metallic strip *u* while convenient and desirable, are not essential, and the connection of the collector brush *h* with the brush *f* may be made directly, by extending the cable *m* to the metallic lining *k'* of the collector brush.

The radial bores *t* are preferably made to fit snugly upon the exterior insulations *o*, *o'*, *o²*, etc., of the cables, but their ends may also be closed air tightly with cement. This prevents moisture, or oil penetrating into the connections of the metallic cores *q* of the cables with the linings *k*, and as the cover *a'* is tightly fitted upon the distributor casing, no part of the metallic connections, or of the apparatus, is exposed, and the danger of dampness, or rain, or oil penetrating into the connections, or into any part of the apparatus, is safely avoided.

I claim as my invention:

1. A connector for electrical conductors, comprising a casing of insulating material, having a recess and a bore communicating therewith; a metallic lining, perforated in line with the bore in the casing, set in the recess; means for securing an electrical conductor inserted in the metallic lining through the bore in the casing, in electrical contact therewith, and an electrical contact

set in, and electrically connected with, the metallic lining; substantially as herein shown and described.

2. A connector for an electrical contact and an electrical conduit, comprising a casing of insulating material having an interiorly screw-threaded recess and a bore from its periphery to the recess, a tubular exteriorly screw-threaded metallic lining set in the recess; an insulated cable snugly fitted into the bore, and means for securing it therein and in electrical contact with the metallic lining; a carbon brush and means for yieldingly supporting it therein, set in the lining and electrically connected therewith; substantially as herein shown and described.

3. A distributor casing, having interiorly screw-threaded recesses and radial bores running parallel to the exterior surface of the casing from its periphery to the termini of the recesses; a tubular, exteriorly screw-threaded metallic linings set in the recesses; carbon brushes set in the linings and means for pressing the brushes in contact with the distributor disk; insulated cables, snugly fitted into the bores, and means for securing the cables therein and in electrical contact with the metallic linings; substantially as herein shown and described.

EUGENE GASSMANN.
